UNITED STATES PATENT OFFICE.

IRVING J. BALL, OF BROCK, NEBRASKA.

ROTARY CARRIER AND ELEVATOR.

No. 834,244.

Specification of Letters Patent.

Patented Oct. 30, 1906.

Application filed May 31, 1905. Serial No. 263,131.

To all whom it may concern:

Be it known that I, IRVING J. BALL, a citizen of the United States, residing at Brock, in the county of Nemaha and State of Nebraska, have invented certain new and useful Improvements in Rotary Carriers and Elevators, of which the following is a specification, reference being had therein to the accompanying drawings.

- 10 This invention relates to improvements in rotary elevators and carriers which, though susceptible of various uses, are primarily designed for utilization in connection with corn gathering and husking machines such as
15 disclosed in my copending application, Serial No. 228, 540, and in general particulars the present device is the same as that originally set forth and claimed in said application and which claims will be hereinafter submitted.
20 The desirable characteristics of a device made in accordance with the present invention will appear upon an inspection of the detailed description hereinafter contained when read in connection with the accompanying
25 drawings, forming part hereof, and wherein a convenient embodiment of the invention is illustrated.

In the drawings, Figure 1 is a vertical sectional view of the rotary elevator and carrier, 30 the same being shown as associated with such fragmentary portions of the corn gathering and husking machine as are necessary to a complete understanding of the purposes for which said elevator and carrier has been devised. Fig. 2 is a detail side elevation. Fig. 3 is a detail perspective, and Fig. 4 a bottom view.

Referring more specifically to the drawings, wherein like reference characters refer 40 to corresponding parts in the several views, and it being borne in mind that the rotary elevator and carrier is adapted especially for use in a machine wherein ears of corn are cut from their stalks and the opposite sides of said ears alternately presented to husking instrumentalities, K designates a series of ways beneath the elevator and carrier running longitudinally of the machine and formed by circumferential ribs or flanges M
45 on the carrier, the latter being represented at N, said ways being for the purpose of guiding stalks which have previously been bent downwardly toward the ground and alining or straightening them for presenta-

tion to the guide-fingers O at the rear of the 55 machine. It will be noted that these ways are continually maintained without interfering with the rotary movement of the elevator and carrier, also that any desired number of said ways may be provided in keeping with 60 the principle involved to adapt the machine to any particular use or capacity.

The guide-fingers O above referred to are arranged so that the spaces therebetween properly register with the ways K, it being 65 unnecessary to otherwise refer to the details of these fingers, inasmuch as they are not of the essence of the present invention. As the stalks pass through the ways K their attached or lower ends first enter the spaces between 70 the guide-fingers and as the machine moves forward are drawn therethrough, whereby the ears are caught between the fingers and guided thereby to a cutter-bar R, which cuts the same from its butt and stalk, when the 75 detached ear is in position for the succeeding manipulation, as will now appear.

It is to be noted that as the machine travels in a forward direction and the ears are engaged by the guide-fingers O the separation 80 of said ears from their stalks is strongly resisted by reason of the stalks holding fast to the ground, so that when the ears are cut from the stalk by the cutter-bar R they project forwardly at substantially right angles 85 to the cutter-bar in position to have their pointed end caught by some of the teeth n, disposed around the periphery of the rotary carrier N. This effects a reversal of the separated ears endwise, whereby they are carried 90 through the machine point first. The ears being carried in an upward direction by the carrier and elevator N, as indicated by the arrow, Fig. 1, the same are engaged by a toothed roller S, rotating in the direction of 95 the arrow, same figure, whereby the ears are elevated or pushed upwardly into the space between the rotary husking devices T and the carrier N. This pushing-roll has several flanges s in line with the flanges M on the carrier N, whereby the proper alinement of the ears is maintained. At this point the outer half or face of the ear is husked. The ears having now been stripped of the husks on one side thereof are carried upwardly and 100 around the top of the machine by the rotary elevator and carrier N until they approach the husking instrumentalities for the oppo-

site sides of the ears mounted at the forward end of the machine, said ears having in the meantime been held in place upon the teeth of the carrier by freely-mounted gravity pressure-rolls X, the shafts x of which work in slots x' in arched side members x'' of the frame of the machine. It is unnecessary to herein set forth the special operation of the second husking devices, it being sufficient to state that they are represented at Y and are designed to remove the husks from the opposite sides or halves of the ears which remain after the first husking operation.

Any convenient means may be provided for properly rotating the elevator and carrier, in this instance the sprocket-wheel 10, driven from any suitable source of power through the medium of a sprocket-chain 9, being shown.

The form of the elevator and carrier is that approximating a hexagon, the flat surfaces of which permit the corn carried thereby to lie flat thereon; but it is obvious that any-shaped carrier found practicable—for example, one having a greater or less number of sides—may be substituted for that disclosed.

Another feature of importance not heretofore observed is the disposition of the teeth n on the periphery of the rotary carrier N. In Fig. 4 it will be seen that these teeth are arranged in pairs disposed at different distances apart, but the teeth of each pair being so separated that they will not engage the center or thickest portion of the ears, but rather at points at the sides thereof, which will give a firm hold on the husks and enable their ready removal without otherwise damaging the corn.

Bolted to the spokes or heads at the ends of the elevator and carrier and immediately underlying the bars to which the teeth n are secured, whereby to peripherally inclose the whole of the interior chamber of the elevator and carrier, is a continuous apron or plate V, adapted to collect any shattered corn which may be shattered from the ears during the rotation of the carrier and discharge the same into a box W, placed at a point beneath and substantially tangentially of the forward portion of the carrier. This apron also serves the additional function of firmly bracing or tying together the heads or ends of the carrier, as is obvious.

It is to be understood that the invention is susceptible of embodiments other than that disclosed herein.

Having thus described the invention, what is claimed as new, and desired to be secured by Letters Patent, is—

1. A device of the character described, comprising a rotary carrier for ears of corn having a periphery forming substantially flat surfaces on which the ears may rest and provided with a series of pairs of short sharp-pointed teeth around said periphery, the teeth of each pair being arranged side by side and separated to bite into the husks at the sides of the ears to hold said ears in a predetermined position on the carrier.

2. A device of the character described comprising a rotary carrier having a plurality of pairs of teeth disposed around its periphery, the teeth of each series being arranged side by side axially of the carrier and separated to bite into the husks at the sides of the ears and to hold said ears in a predetermined position on the carrier, and self-adjustable means arranged in substantially the same arc as the upper run of the carrier and thereabove for preventing disengagement of the ears from the teeth.

3. A device of the character described comprising a rotary carrier having a plurality of pairs of teeth disposed around its periphery, the teeth of each series being arranged side by side axially of the carrier and separated to bite into the husks at the sides of the ears and to hold said ears in a predetermined position on the carrier, and self-adjustable means arranged in substantially the same arc as the upper run of the carrier and thereabove for preventing disengagement of the ears from the teeth.

4. In a machine of the character described, a carrier provided with teeth for engaging the ears, and gravity-rolls for preventing disengagement of the ears from said teeth.

5. In a machine of the character described, a carrier provided with teeth for engaging the ears, and a series of rolls arranged transversely of the carrier with their axes at right angles to the direction of movement of the carrier for preventing displacement of the ears from their initial position of engagement by said teeth.

In testimony whereof I affix my signature in presence of two witnesses.

IRVING J. BALL.
